UNITED STATES PATENT OFFICE.

LOUIS BULASKY, OF NEW YORK, N. Y.

HAT-TRIMMING MACHINE.

1,059,341.

Specification of Letters Patent. Patented Apr. 22, 1913.

Application filed July 30, 1912. Serial No. 712,268.

To all whom it may concern:

Be it known that I, LOUIS BULASKY, a citizen of the United States, residing in the borough of Brooklyn of the city of New York, in the county of New York, in the State of New York, have invented certain new and useful Improvements in Hat-Trimming Machines, of which the following is a specification, reference being had to the accompanying drawings, which form a part hereof.

This invention relates particularly to machines for trimming the edges of felt hats and in which the felt is fed by two co-operating presser wheels, the cutting being effected simultaneously by a circular knife, which rotates with the upper presser wheel and co-operates with the lower presser wheel. In machines of this character, as heretofore used, both presser wheels are mounted upon relatively fixed shafts, and one feed wheel, usually the upper, has a central aperture larger than the shaft or gear hub upon which it is mounted so that it may yield slightly to accommodate varying thicknesses of felt, the feed wheel being driven only by frictional contact with the face of the gear or of a disk affixed to the gear. The friction driving of the feed wheel, which was a necessary result of this construction, leads to irregularities in the feed and one object of the present invention is to improve the construction so that, while the presser wheel may yield vertically to accommodate varying thicknesses of felt, it shall yet be driven positively so that it cannot have driving slip; at the same time provision is made for regulating the friction between the feed wheel and its driver, so that it may yield upwardly more or less easily as the conditions of the work may require.

Another object of the invention is to provide means for lifting the upper feed wheel clear of the lower feed wheel for the purpose of clearing the work from the feed wheel.

Still another object of the invention is to provide means for regulating the downward pressure of the upper feed wheels.

50 Still another object is to provide means for effecting a relative displacement of the two feed wheels horizontally for the pur-

pose of enabling the work to be removed and inserted readily.

The invention will be more fully explained hereinafter with reference to the accompanying drawings in which it is illustrated and in which—

Figure 1 is a view in front elevation, partly broken out, of a felt trimmer which embodies the several features of the invention. Fig. 2 is a top view of the same. Fig. 3 is a detail view in section on the plane indicated by the line 3—3 of Fig. 1, looking in the direction of the arrows. Fig. 4 is a similar view, showing the upper feed wheel raised from the lower feed wheel, the knife being partly broken away. Fig. 5 is a detail view in section on the plane indicated by the line 5—5 of Fig. 1, looking in the direction of the arrows. Fig. 6 is a detail view in section of the adjustable spring plunger for applying pressure to the upper feed wheel. Fig. 7 is a detail view in section, and on a somewhat larger scale than that of Figs. 1—5, illustrating particularly the devices for mounting the upper feed wheel and knife with relation to the lower feed wheel. Fig. 8 is a detail view in section on the plane indicated by the broken line 8—8 of Fig. 7, looking in the direction of the arrows. Fig. 9 is a face view of the driving disk. Fig. 10 is a face view of the upper feed wheel.

The machine shown in the drawings comprises a frame *a* having a lower arm *a'* and an upper arm *a''*, all suitably shaped to support the working parts. The frame is provided with a stud *a³* upon which is mounted a grooved driving pulley *b*. A pinion *b'* on the hub of the driving pulley meshes with a gear wheel *b²* on a shaft *b³* mounted in suitable bearings in the frame, while a gear wheel *b²* meshes with a corresponding gear wheel *c* fixed on a shaft *c'* which is mounted in suitable bearings in the lower arm of the frame and carries the lower feed wheel *c²*. Provision is made whereby the lower feed wheel *c²* may be displaced horizontally with respect to the upper feed wheel. A collar *c³* is fixed on the shaft *c'* and its hub *c⁴* is threaded to receive a sleeve *c⁵* against the end of which rests a washer *c⁶*. A spring *c⁷*, bearing at one end against the bearing *c⁸*,

- rests at its other end against the washer and so tends to hold the shaft c' and the feed wheel c^2 in their normal position. The sleeve c^5 is adjustable on the hub c^4 so as to permit the tension of the spring to be adjusted. Loosely mounted on the shaft c' and between the collar c^3 and the vertical arm a^8 of the frame, is a collar c^9 which carries a cam c^{10} provided with a handle c^{11} .
- 10 The cam c^{10} bears against an abutment a^4 on the frame and is provided with a dwell, as indicated at c^{12} . When the handle c^{11} is in the position shown in Figs. 1 and 5 the feed wheel c^2 is permitted to occupy its normal operative position, but when the handle is turned up to or toward the horizontal position the shaft c and the lower feed wheel c^2 are moved to the left to throw the lower feed wheel out of line with the upper feed wheel, as shown by dotted lines in Fig. 1.
- 15 The shaft b^3 is provided as usual with a pinion b^4 , indicated by dotted lines in Fig. 3, which meshes with an idler b^5 , while the latter in turn meshes with a pinion b^6 , all as indicated by dotted lines in Fig. 3 and as shown in Fig. 7. The idler b^5 may be mounted upon a stud b^7 and the pinion b^6 upon a longer stud b^8 , both secured in the head a^5 of the frame. The pinion b^6 is formed with or secured to the hollow shaft or sleeve d and is recessed as at d' to receive an independent, loose bearing ring d^2 . Screws d^3 , inserted from the opposite face of the pinion b^6 , support the bearing ring d^2 so that it may be crowded more or less against the adjacent member, which is the driving disk d^4 . The latter is slotted, as at d^5 , to engage a stud d^6 on the sleeve d , so that the driving disk shall be driven positively with the pinion b^6 but may be moved relative thereto by the ring d^2 and screws d^3 .
- 20 The upper driving wheel e has a central aperture e' sufficiently large to permit considerable movement of the driving wheel with respect to the sleeve d and it has also, on its face adjacent to the driving disk d^4 , pins e^2 which enter enlarged recesses d^7 in the adjacent face of the driving disk, so that the feed wheel may have considerable vertical movement with respect to the axis of the sleeve d , but shall nevertheless be driven positively from the driving disk d^4 . A washer f , having a flanged hub f' , is received on the sleeve d against the right hand face of the feed wheel e , the hub f' being preferably slotted so as to engage a stud d^8 on the sleeve d , whereby the washer also is driven positively with the pinion b^6 .
- 25 The knife g fits snugly upon the reduced right hand end of the sleeve d and is held against the shoulder d^{10} by a nut g' , so that the knife is driven positively with the pinion b^6 . The knife g forms an abutment for the washer f and the feed wheel e so that the friction between the feed wheel e and

the washer f on the one side and the driving disk d^4 on the other side may be regulated by crowding the ring d^2 against the driving disk d^4 by means of the screws d^3 against which the ring d^2 rests.

30 The upper feed wheel e is lifted, to clear the lower feed wheel, by a lifter h which partly encircles the feed wheel at its front edge. At its rear edge the feed wheel bears against a fixed guide h' to prevent the feed wheel from being crowded to the rear when the lifter acts. The lifter may be operated by any convenient means, but preferably is arranged to be operated by the same controller handle by which the horizontal displacement of the lower feed wheel c^2 is effected. For this purpose the stem h^2 of the lifter, mounted in guides h^3 and pulled normally down by a spring h^4 , is connected at its upper end with a lever h^5 which is pivoted at h^6 on the upper frame a^2 of the frame and is connected at its other end by a link h^7 with the hub c^9 of the cam c^{10} , so that when the cam is rotated to displace the lower feed wheel horizontally, the upper feed wheel is at the same time lifted vertically. In order that the lifting movement of the upper feed wheel may take place after the lateral movement of the lower feed wheel has been accomplished, lost motion is provided for, preferably by a slotted link h^8 to which the link h^7 is connected, while it is itself loosely held to the top of the cam by a screw h^9 which passes through the slot of the short link and enters the hub of the cam.

35 In order that the upper feed wheel may be pressed downward with an adjustable but yielding pressure there is provided an adjustable spring presser h which comprises a plunger h' having in its extremity a roller h^2 to bear against the periphery of the upper feed wheel and guided in a cylinder h^3 . A spring h^4 , placed within the cylinder, bears against the plunger h' and its tension may be adjusted by a follower h^5 and adjusting screw h^6 which is threaded in the cap of the cylinder.

40 The operation of the improved cutter is the same in general as that of prior cutters although it differs in certain details which have now been explained and require no further description herein.

45 It will be understood that various changes may be made in the details of the parts to suit different conditions of use and is not limited to the precise construction shown and described herein.

50 I claim as my invention:

- 55 1. The combination of an upper feed wheel, a lower feed wheel, a shaft upon which the lower feed wheel is mounted, said shaft being movable longitudinally, a collar on said shaft, an edge cam mounted loosely on the shaft, and a fixed abutment to cooperate with said cam.

2. The combination of an upper feed wheel, a lower feed wheel, a shaft upon which the lower feed wheel is mounted, said shaft being movable longitudinally, a collar 5 on said shaft, an edge cam mounted loosely on the shaft, a fixed abutment to coöperate with said cam, and a spring acting upon said shaft in opposition to the cam to hold the feed wheel in normal position.
- 10 3. The combination of an upper feed wheel, a lower feed wheel and a driving disk, one of the feed wheels being movable with respect to the driving disk and said last named feed wheel and the driving disk 15 having coöoperating pins and enlarged recesses whereby the positive driving of said feed wheel from the driving disk is effected while relative movement is permitted.
4. The combination of an upper feed 20 wheel, a lower feed wheel, a rotating shaft upon which the upper feed wheel is mounted, said upper feed wheel having a central aperture larger than the shaft, and a driving disk mounted on the shaft to rotate therewith, the upper feed wheel and the driving disk having coöoperating pins and enlarged recesses whereby said upper feed wheel is driven positively but with freedom for relative displacement.
- 25 5. The combination of a driving shaft, a driving disk mounted thereon to rotate therewith, a feed wheel loosely encircling the driving shaft, said driving disk and feed wheel having coöoperating pins and enlarged recesses, a flanged washer mounted on the shaft to rotate therewith, an abutment to support said washer, and means to crowd the driving disk and the feed wheel together and toward the washer.
- 30 6. The combination of a driving pinion recessed on one side, a shaft for said pinion, a bearing ring located in the recess, screws carried by the pinion and against which the bearing ring rests, a driving disk mounted 35 on the shaft to rotate therewith and resting against said bearing ring, a feed wheel mounted loosely on the shaft, said driving disk and feed wheel having coöoperating pins and enlarged recesses, a washer mounted 40 on the shaft to rotate therewith and against which the feed wheel bears, and an abutment for said washer.
7. The combination of a supporting head, a stud secured thereto, a sleeve mounted on 45 said stud and provided with a pinion, a driving disk mounted on the sleeve to rotate therewith and a feed wheel mounted on the 50 sleeve, said driving disk and feed wheel having coöoperating pins and enlarged recesses and the feed wheel having an enlarged central aperture to encircle the sleeve loosely.
- 60 8. The combination of a driving shaft, a driving disk thereon, a feed wheel loosely encircling the shaft and operatively engaged in the driving disk, and a presser bearing upon the periphery of the feed wheel to hold it to its work.
- 65 9. The combination of a driving shaft, a driving disk thereon, a feed wheel loosely encircling the shaft and operatively engaged in the driving disk, and a spring pressed plunger bearing upon the periphery of the feed wheel to hold it yieldingly to its work.
- 70 10. The combination of a driving shaft, a driving disk thereon, a feed wheel loosely encircling the driving shaft and having an operative engagement with the driving disk, and a lifter partly encircling the driving disk.
- 75 11. The combination of a driving shaft, a driving disk thereon, a feed wheel loosely encircling the driving shaft and having an operative engagement with the driving disk, and a lifter guide coöperating with the feed wheel opposite the lifter.
- 80 12. The combination of a driving shaft, a driving disk thereon, a feed wheel loosely encircling the driving shaft and having an operative engagement with the driving disk, a lifter and means to actuate the lifter.
- 85 13. The combination of an upper feed wheel and a lower feed wheel, the one movable toward and from the other, and the other movable laterally with respect to the first, and common actuating means whereby the described movement of said feed wheels is effected.
- 90 14. The combination of an upper feed wheel and a lower feed wheel, the one movable toward and from the other, a lifter coöperating with the first of said feed wheels, a longitudinally movable shaft upon which the other of said wheels is mounted, a cam to shift said shaft longitudinally, and a common actuating means for said lifter and said cam.
- 100 15. This specification signed and witnessed this 29 day of July A. D., 1912.

LOUIS BULASKY.
